UNITED STATES PATENT OFFICE.

JAMES J. GOUGH, OF CHICAGO, ILLINOIS, ASSIGNOR TO CHICAGO ELECTRIC MANUFACTURING CO., OF CHICAGO, ILLINOIS, A CORPORATION OF ILLINOIS.

ELECTRIC SWITCH.

Application filed June 27, 1927. Serial No. 201,715.

My invention relates to electric switches of the class employing an oscillating switching member, and more particularly to the type of such switches in which the switching member slides back and forth parallel to the front or face-plate of the switch.

Generally speaking, it is the object of my invention to provide an unusually simple, inexpensive and easily assembled switch of this general type. More particularly, my invention provides a reciprocating switch in which a simple punching co-operates with a back plate to form an effective switch casing and to guide the reciprocating member of the switch, in which the switching member contacts directly with the wire terminals, and in which the switching member is positively halted when moved in either direction. It also provides a switch of this type in which the switching member is formed so as to impart a snap or quick-throw movement to the reciprocating member, and in which the resiliency of the switching member operates for latching the reciprocating member both in its "on" and in its "off" position.

Furthermore, my invention provides a switch consisting of very few parts and so constructed as to require no auxiliary fastening members for retaining these parts in their assembled relation. It also provides a reciprocating member including a carrier and one or more switching members slidably insertible in the carrier and retained on the carrier by their own resiliency, and provides a carrier construction which will prevent a reversed attaching of the switching member or members. Moreover, my invention provides a carrier having stop shoulders disposed for engaging one or the other of the two contact terminals to limit the movement of the carrier in each direction, and arranged so that the engagement of the terminals with a switching member will hold one or the other of the said terminals yieldingly against one of the said shoulders.

In another object, my invention provides a reciprocating member including two switching members mounted on a single carrier and respectively engaging opposite sides of the terminals, and provides switching members formed so that their said simultaneous engagement will intensify the pressure of the said members against the terminals. My invention also provides a carrier slidable over

the two terminals and having an integral formation disposed for engaging either terminal to limit the movement of the carrier in either direction, and provides novel means for securely interlocking either one or two switching members with the carrier without requiring auxiliary fastening elements of any kind. Moreover, my invention provides a switch construction in which the terminals guide the reciprocating member independently of other parts, thereby insuring a proper alignment regardless of variations in the manufacture or assembly of the switch parts.

Still further and also more detailed objects will appear from the following specification and from the accompanying drawings, in which—

Fig. 1 is a front elevation of a switch embodying my invention, with the reciprocating member in the "off" or circuit-opening position of the switch.

Fig. 2 is an end elevation of the same.

Fig. 3 is a side elevation of the same.

Fig. 4 is a central and longitudinal section, taken along the line 4—4 of Fig. 1, with one of the wire terminals in section.

Fig. 5 is a rear elevation of the switch with the base detached and with the reciprocating member in the "off" position.

Fig. 6 is a view similar to Fig. 5, but with the reciprocating member in the "on" or circuit-closing position.

Fig. 7 is a rear elevation of the carrier or insulating portion of the reciprocating member of the switch of Figs. 1 to 6.

Fig. 8 is a view similar to a portion of Fig. 5, showing the use of a single switching member in an allied embodiment.

Fig. 9 is a view allied to a portion of Fig. 5, but showing an embodiment in which a single switching member has a portion disposed for limiting the travel of the reciprocating member.

Fig. 10 is a front elevation of the detached base and the contact terminals mounted on it.

Fig. 11 is a reduced perspective view of the main metal frame members of the switch.

In the embodiment of Figs. 1 to 7 inclusive, my switch includes a rigid two-piece frame in which the reciprocating member is slidably mounted, which frame-like structure suffices in place of more complete casing when the major portion of the switch is disposed within a recess in a wall to which his face-

plate is fastened. This frame includes as one member a face-plate 1 having the usual screw-holes 2 and also provided with a central and rectangular slot 3; and a pair of side webs 4 extending rearwardly from the face-plate 1 longitudinally parallel to and at opposite sides of the said slot, each web having a finger 5 in extension of its rear end. The companion member of the frame is an insulating disk 6 which forms the base of the switch, this base being provided with perforations 7 through which the fingers 5 respectively extend, each finger having its rear end bent against the rear of the base 6 to clamp this base against the free ends of the side webs 4.

15 Mounted on the base 6 are two spaced metal terminals 8 and 9 having parallel stems extending at right angles to the base 6 toward the face-plate 1, each terminal being clinched to the base as shown in Fig. 4. Each terminal has a longitudinal bore, threaded to fit the shank of a binding screw 10 which has its head disposed behind the switch and adapted to clamp an interposed wire against the rear end of the corresponding terminal.

20 Extending between the side webs 4 is a carrier 13 of insulating material of a thickness approximating the width of the webs 4, so that this carrier is slidably interposed between the face-plate and the base of the switch. The carrier also has an integral button 11 projecting forwardly through the slot 3 in the face-plate, which button may be guided laterally by edges of this slot. The 25 forward end of the button 11 is preferably knurled to facilitate the digital sliding of the reciprocating member of my switch, and the front of the main portion of the carrier desirably has an indicating mark (such as the white dot 12 of Fig. 1) so disposed beyond one 30 end of the button that this mark will only be visible when the switching mechanism is in its "off" position.

35 The carrier 13 desirably is substantially channel-shaped in transverse section, with the channel opening rearwardly and freely straddling the stems of the terminals 8 and 9. Extending longitudinally within the channel are two switching members, formed of flat 40 spring bronze or the like, each of which is secured intermediate its ends to the carrier so as to present two contact arms respectively disposed for contacting with the two terminals. Each arm of either switching member desirably has a hump directed toward the other switching member and adapted to ride over the adjacent terminal when the carrier is moved from the "on" to the "off" position, or vice versa. The carrier also has means, desirably in the form of an integral bridge 15 extending across the channel, for engaging either terminal, according to the direction in which the carrier is moved, so as to limit the travel of the carrier; and in each of its thus 45 limited positions the bridge-engaging termi-

nal is yieldingly held against the bridge by the hump formations on the two spring contact arms engaging that terminal.

50 Thus, in the "off" position of the switch (Fig. 5), the humps on the spring arms 15 A and 16 A press the terminal 8 against the shoulder formed by the left-hand face of the bridge 17, while the other spring arms 15 B and 16 B are out of contact with the other terminal 9. In the "on" position (Fig. 6), 55 the humps on the arms 15 B and 16 B press the other terminal 9 against the right-hand shoulder face of the bridge, and the humps on the contact arms 15 A and 16 A engage the terminal 8 so as to augment this pressing. 60 Consequently, the reciprocating member of the switch is latched against accidental movement both in its "on" and its "off" position. Since the humps of at least one pair of contact arms ride over an interposed terminal 65 when the switch is moved from one of its said positions to the other, I also secure a snap or quick-throw action.

65 To secure the switching members to the carrier without requiring auxiliary fastening elements, I desirably provide two slits 18 extending through the bridge adjacent to the channel walls, and enlarge each of these slits intermediate its ends, as for example by providing bores 19 respectively intersecting the 70 two slits. Then I form a hump 20 on each switching member between alined parts which substantially extend through the slit portions at opposite sides of the adjacent bore 19. With the carrier thus formed, as shown in 75 Fig. 7, these alined parts of a switching member (such as the parts 15 C and 15 D of Figs. 5 and 8) can be slid into the said slit parts, while the intermediate hump 20 enters the bore 19 and engages the walls of this bore 80 so as to prevent the switching member from sliding longitudinally of the carrier. By making each switching member of a thickness approaching the width of the slits 18, I 85 can readily anchor this member to the carrier without requiring a rivet or other fastening means. However, no accurate interfitting is required, as the back of the channel and the base 6 of the switch will cooperate with the said hump and bore formations for retaining the switching members on the carrier in substantially fixed positions.

90 When the reciprocating member (consisting of the carrier 13 with its integral button 11 and the two inserted switching members 15 and 16) is slipped over the terminals on the insulating base, the engagement of the opposed contact arms with opposite sides of the terminals alines the axis of the carrier substantially with a plane axial of both terminals, so that no accurate interfitting of the button 11 with the slot 3 in the face-plate is required. Consequently, I can allow some lateral play for this button, and trifling variations in the manufacture or assembly of 95 100 105 110 115 120 125 130

the switch parts will not interfere with its operation.

Since the contacts directed toward one end of the carrier are intermittently in and out of contact with the adjacent terminal, these arms are shorter than the other arms which continuously engage the terminal interposed between them. To avoid having the switching members slid into the carrier slits in a reversed position, I desirably contract the channel at the end which is to be opposite the short arms, as by providing lugs 21. With this provision, the entire assembly of my switch is exceedingly simple and can readily be performed without confusion even by inexperienced hands.

However, while I have heretofore described my invention in an embodiment including two switching members (which will intensify the pressure on the terminals in the "on" position of the switch), and as including a stop bridge on the carrier, I do not wish to be limited to these or other details of the construction and arrangement thus disclosed. Obviously, many changes might be made without departing either from the spirit of my invention or from the appended claims.

For example, a single switching member of the previously described form might be employed, as shown in Fig. 8. Or, a single switching member of substantially Z-shape might be used with a channel-shaped carrier after the manner of Fig. 9, with the intermediate shank extending across the channel so as to engage one or the other terminal for halting the movement of the reciprocating switch member in both directions.

Moreover, I do not wish to be limited to the use of my switching mechanism in combination with a slotted face-plate or with any particular connection between the switch parts which guide the reciprocating member.

I claim as my invention:

1. An electric switch comprising a base, a pair of spaced and relatively insulated terminals mounted thereon, a stop member disposed between the terminals and slideable with respect to the base into engagement with one or the other terminal, a pair of switching members fast on the stop member and extending respectively at opposite sides of both terminals; the switching members being disposed to contact continuously with one terminal and to contact with the other terminal only when the latter is engaged by the stop member.

2. In an electric switch, a pair of spaced metal terminals, a channel-shaped insulator straddling both terminals, a resilient contact member disposed within the channel of the insulator secured intermediate its ends to the insulator and having arms respectively engaging the two terminals when the insulator is in one position, and a mounting for the

terminals and insulator in which the insulator is slideable to another position in which only one arm of the contact member engages a terminal.

3. An electric switch as per claim 2, in which the other arm of the contact member has a hump riding over the terminal engaged by that arm during the movement of the insulator from one to another of its said positions. 75

4. In an electric switch, a housing including a pair of parallel plates, the front plate having a slot therein; two relatively insulated wire terminals mounted on the rear plate and extending into the space between the plates; a reciprocable member slidably disposed between the two plates and having an actuating button projecting through but shorter than the slot; and a resilient contact member carried by the said member and adapted to contact with one or both of the terminals according as the button is adjacent to one or the other end of the slot, the said member having an integral stop portion disposed between the wire terminals and shorter than the distance between the terminals and adapted to engage either terminal to limit the movement of the said member in opposite directions. 80 90

5. In a reciprocating switch, a pair of spaced terminals having parallel axes, a carrier mounted for slideable movement transverse of the said axes and substantially in the common plane of the said axes, a pair of contact members carried by the carrier and respectively at opposite sides of the said plane, and means for limiting the movement of the carrier in both directions; the contact members being arranged so that both thereof continuously engage one contact member, and so that both thereof are brought into and out of engagement with the other contact member when the carrier is moved respectively to its said limited extent in opposite directions. 95 100 105 110

6. A switch as per claim 5, in which the said limiting means comprise shoulders on the carrier between the two terminals and disposed for respectively engaging the two terminals according to the direction in which the carrier is moved. 115

7. A switch as per claim 5, in which the said limiting means comprise shoulders on the carrier disposed for respectively engaging the two terminals according to the direction in which the carrier is moved, the contact members being formed for yieldingly holding the engaged shoulder against the terminal engaging it. 120

8. In an electric switch, a casing including a front plate provided with a slot and an insulating back plate; a pair of wire terminals having stems projecting from the back plate toward the front plate; a reciprocable member including a button projecting through 125 130

- the said slot and a pair of insulating webs extending parallel to the slot at opposite sides of the said stems and slidably guided by the two plates; means to limit the travel of the reciprocable member; and a contact member mounted on the reciprocable member and having two resilient portions, the first of which continuously engages one of the stems in all positions of the reciprocable member, the other resilient portion being in and out of contact with the other stem when the reciprocable member is respectively at opposite ends of its travel.
9. An electric switch as per claim 8, in which the first named resilient portion of the contact member has a hump which rides over the stem engaged by that portion during the movement of the reciprocable member from the "on" to the "off" position of the switch.
10. An electric switch as per claim 8, in which the contact member comprises a flat strip of resilient member having a medial portion secured to one web of the reciprocable member, and having two resilient arms extending in opposite directions from the said medial portion and forming the said resilient portions.
11. An electric switch as per claim 8, in which the contact member comprises a flat strip of resilient member having a medial portion secured to the reciprocable member, and having two resilient arms extending in opposite directions from the said medial portion and forming the said resilient portions; the slideable member having a slit in which the said medial portion of the contact member is inserted, the said slot and medial portion having interengaging formations to prevent the contact member from moving longitudinally of the said slit.
12. In an electric switch, a housing including a pair of parallel plates, the front plate having a slot therein; two relatively insulated wire terminals mounted on the rear plate and extending into the space between the plates; a carrier slidably disposed between the two plates and having an actuating button projecting through but shorter than the slot; and a pair of resilient contact members mounted on the carrier and spaced transversely of the slot and extending at right angles to both plates; both of the contact members being of such a length as to engage one terminal continuously, and to engage the other terminal only when the button is substantially at one end of the slot, the two contact members being disposed for engaging opposite sides of the terminals.
13. An electric switch comprising a base, a pair of relatively insulated terminal posts projecting forwardly from the base, and a slideable member including a stop portion disposed between the said posts and adapted to engage either post, the slideable member also including two metallic and resilient switching members respectively at opposite sides of both posts, the switching members being formed for engaging both posts when the said stop portion engages one of the posts and for engaging only one post when the stop portion engages the other post.
14. A switch as per claim 13, in which the sliding member has slits in its stop portion through which the two switching members respectively extend.
15. A switch as per claim 13, in which the sliding member has slits in its stop portion through which the two switching members respectively extend, and in which the said stop portion and each switching member have interengaging formations to prevent longitudinal sliding of the switching member from sliding upon the stop portion.
16. A switch as per claim 13, in which the two switching members slope toward each other from their medial portions to a normal distance less than the diameter of each post, the said sloping causing the switching members in the extreme position of the sliding member to press the said stop portion respectively against one or the other post.
17. An electric switch comprising an insulating base, a pair of spaced terminal posts extending forwardly from the base, a front plate parallel to the base, an insulator slideable between the latter and the front plate and including a stop portion extending between the posts transversely of a plane through the axes of both posts, and a pair of metallic and resilient switching members mounted on the insulator and both bowed towards both posts and extending past opposite sides of the stop portion; the switching members being formed so as to engage opposite sides of both posts when the insulator is slid so that the stop portion engages one post, and the switching members being so formed as to engage only the last named post when the other post engages the stop portion.

Signed at Chicago, Illinois, June 21st 1927.

JAMES J. GOUGH.
